UNITED STATES PATENT OFFICE.

WILLIAM S. CLYMER, OF WESTERVILLE, OHIO.

NUT-LOCK.

SPECIFICATION forming part of Letters Patent No. 314,112, dated March 17, 1885.

Application filed May 29, 1884. (No model.)

To all whom it may concern:

Be it known that I, WILLIAM S. CLYMER, a citizen of the United States, residing at Westerville, in the county of Franklin and State of Ohio, have invented certain new and useful Improvements in Nut-Locks, of which the following is a description.

This invention relates to that class of devices used to prevent screw-nuts from working loose from the bolts on which they are used; and its object is to secure a nut positively from turning backward, to adjust the locking parts closely, and to secure them at different points in a revolution, and to secure the locking parts from being lost.

To this end my invention consists in the construction and combination of parts forming a nut-lock, hereinafter described and claimed, reference being had to the accompanying drawings, in which—

Figure 1 is a plan view of my invention. Fig. 2 is an end view, and Fig. 3 is a plan view, of a modification thereof; and Fig. 4 is a longitudinal section of the principal device.

25 A represents a screw-bolt having a longitudinal slot, a.

B is a screw-nut fitting the bolt and countersunk in its outer face at b, Fig. 4.

C is a common washer. 30 D is the lock-nut, threaded to fit the bolt, and provided with a number of grooves, f, across its inner face, just outside of a line tangent to the screw.

E is a key fitting the slot a in the bolt and 35 projecting beyond the circumference thereof.

d represents a series of slots in the lock-nut D, either one of which will register with the slot a, and will permit the key E to pass through it.

40 The key E is provided with a series of transverse notches, e, any one of which may register with any one of the grooves f; and F is a wire, tapered to be driven through a groove, f, and through a notch, e, when the nut D is screwed home against the nut B and the key is seated.

In use, the nut B is first screwed home, then the lock-nut D is screwed against it by straining on it with the wrench a little more or little less, as may be required to register a slot 50 in the nut with the slot in the bolt. Insert the key in place, then drive the wire across through it, and bend the ends of the wire.

The countersink b receives the end of the key far enough to register a notch, e, with a groove, f. The lock-nut stops the main nut, the key stops the lock-nut, the wire stops the key, and the bends in the wire stop it from removal. In course of time the wire might work loose enough to pass its large end through its groove and be lost, so I recommend bending both ends.

To remove the nut it is only necessary to first straighten the small end of the wire, then each part may be in its turn removed.

The countersink in the main nut B is to admit the end of the key enough to bring a notch in register with a groove in the check-nut.

By this method of fastening nuts neither the nut or bolt is in any way bruised or damaged by any number of applications and removals of the lock, and as soft wires are used, even they may be bent and straightened for an indefinite number of applications.

The modification shown in Fig. 3 consists in a slotted washer, G, provided with a groove, f. This is a mere transposition of the groove from the check-nut to the washer, the wire being used in the same manner in either case. In this latter case the nut does not require a groove, f.

As the washer may be turned with the groove f toward the main nut B, I have provided a number of cross-notches e in the key that some one may readily register with the groove under any circumstances.

What I claim as my invention, and desire to secure by Letters Patent, is—

The combination, with a longitudinally-slotted bolt, of a cross-notched key to fit therein, a nut fitted on the bolt and countersunk around the bolt-hole, another nut fitted on the screw-bolt, provided with slots to register with the slot in the bolt and to receive the key, and provided with grooves across its face and across its slots tangent to the bolt-hole, and a wire adapted to fit closely in the said grooves and at the same time to rest in a notch of the said key, substantially as shown and described.

WM. S. CLYMER.
